George N. Goddard

UNITED STATES PATENT OFFICE

GEORGE N. GODDARD, OF NEWTON, MASSACHUSETTS

DEVICE FOR SPINNING AND TWISTING TEXTILE FIBERS

Application filed June 30, 1927. Serial No. 202,680.

This invention relates to the art of spinning or twisting textile fibers, and is intended to provide a simple, convenient and practical device for spinning and twisting fibers which shall overcome or minimize certain practical difficulties experienced in this art as heretofore practiced. The commonly used ring and traveler spinning is open to serious criticism because of its production 10 of imperfect yarn and its liability to frequent breakages of the yarn ends in the spinning operation and consequent waste of roving and loss of production. Moreover, the practical limit of production with the 15 ring and traveler has already been reached in spite of improvements in spindles which would permit a materially higher speed.

The present invention affords a solution 20 of these difficulties by making possible a very substantial increase in speed of production while at the same time improving the quality of the yarn as to strength, elasticity and evenness besides minimizing the 25 breaking of ends and consequent waste and loss of production.

This invention consists primarily in the 30 combination of a loose yarn-engaging ring which serves both as a coping member and a tension member with an annular holder or track member inside of which the coping ring has a continuous rolling or slightly orbital movement under the constant push 35 or driving action of the yarn. The yarn tension produced is due largely to the inertia or resistance to the push of the yarn so that variations in tension may be effected by varying the mass or weight of the rolling ring as well as by such changes in form as 40 will affect the frictional retardation of the yarn in a manner hereinafter to be described. This and other features of the invention will be more precisely pointed out in the following specification and in the claims annexed.

45 While the use of a loose coping ring interiorly mounted in a surrounding holder was proposed nearly a century ago and repeated efforts have been made to devise a 50 spinning device on that principle, the essential requisites to a successful operative spin-

ning device of that type have been so little understood that none of the constructions proposed were capable of even the slightest use for spinning under actual mill conditions. Every such proposed device was 55 based either on the theory of a ring "floating" loosely inside its containing holder or of a frictional drag ring which would be frictionally dragged around by the revolving yarn although at a slower speed. 60

I have discovered that both the "floating ring" theory and the "drag ring" theory are wholly untenable and that successful spinning with a loosely mounted coping ring 65 can be effected only by establishing certain conditions or relations which have heretofore been entirely overlooked.

These conditions must be such as to maintain a true rolling action of the coping ring inside its holder which will result in 70 a relatively slow rotation of the ring in a direction reverse to that of the revolving yarn. To establish such reverse rotation however two things are of vital importance. First, there must be a sufficient clearance 75 space between the interior retaining lip of the holder and the outside of the coping ring to prevent any rubbing contact of the ring-engaged portion of the yarn with the edge of the holding down lip and, second, the yarn contacting surface of the ring must 80 be so smoothly finished as to present practically no frictional engagement with the yarn that will tend to drag the ring in the direction of the yarn, that is, the yarn-engaging surface of the ring must be polished to an extraordinary or microscopic smoothness much beyond the finish given traveler rings now in use. Furthermore, the coping ring must be sufficiently light in weight 85 so that its mass interia will not oppose too much resistance to the revolution of the yarn, a point that has never before been understood since the mass or weight of the rings heretofore suggested has been altogether too great for service even had other requisites been observed.

If the above mentioned conditions are 90 carefully observed it is possible to produce, under various forms, a spinning device 100

greatly superior to the well known ring and traveler in respect to the quality of yarn produced, speed of production and absence of waste, whether lap waste or lint. Such 5 discovery forms the basis of my present invention and its specific application will now be explained as illustrated under several forms in the accompanying drawing, in which;

10 Figure 1 is a vertical cross section in a much enlarged scale illustrating one form of construction.

Figure 2 is a plan view thereof on a somewhat reduced scale.

15 Figures 3, 4, 5 and 6 are similar cross sectional views showing various modifications of the form of coppering ring and holder.

Figure 7 is a detail showing in vertical diametrical section one form of pressed steel 20 ring that may be used in a holder similar to that shown in Figure 6.

Figure 8 is a cross sectional view of a modified ring.

This application is a continuation of my 25 earlier filed allowed application, Serial No. 281,261, filed March 6, 1919, so far as concerns the subject matter or disclosure common to both applications.

The material of which the loose coppering 30 ring is made may be either metal or a non-metal, such as vulcanized fiber or bakelized pulp. As steel is approximately five times the weight of fiber the cross sectional area of the fiber ring may be practically five 35 times as great as that of the steel. If steel be used it would preferably be in the form of pressed steel to obtain the requisite lightness and stiffness of the ring to prevent the unsupported portion of the ring from 40 springing up into the inside of the holding-down lip under tension of an upward pull of the yarn, as will be presently described.

In practice the coppering ring, whether 45 metallic or non-metallic, used for spinning medium counts of filling yarn would have a weight of approximately seven grains, and in any case must be so thoroughly polished on their surfaces exposed to the contact with the yarn as to afford not even the most minute obstruction or scratch that could act to catch and retard the yarn. In short, the yarn-engaging surfaces of the rings should be made as nearly frictionless as it is 50 possible to make them.

55 The ring-engaging or bearing surfaces of the holder should also be very smoothly finished but not necessarily to as high a degree of smoothness as is requisite for the ring.

60 In Figures 1 and 2 I have shown a simple form of ring and holder in which the holder is made in two parts comprising a cast metal base 1, having an upstanding flange 2, provided with an outwardly projecting 65 or overhanging shoulder 3, which may pro-

ject less than one-sixty-fourth of an inch for positively engaging the non-metallic member 5 which, in this case, forms the container for the loose coppering ring 8, and for that purpose is provided with an annular groove 5a formed inside the holder close to the top thereof so as to leave an inwardly projecting retaining lip 6 to overhang the ring and prevent its being pulled from the holder by the yarn. It will be understood that the parts as shown in Figure 1 and even in Figure 2, are on a scale very greatly exaggerated to show fully the details of construction. The holding down lip 6, at its inner edge portion particularly, is very thin in order to prevent contact with the revolving yarn and allow a yarn-admitting slot to be cut through one side of the holder on a substantially radial line. By reducing the inner edge of the lip to a thin edge, say approximately one-sixty fourth of an inch in thickness, the use of a radial yarn admitting slot is possible to give a proper amount of clearance between the coppering ring and the holding-down lip to avoid the catching of the ballooning yarn in the upper portion of such radial slot which would occur unless the edge of the lip is quite thin, owing to the divergence of this portion of the yarn toward the outside. The advantage of this arrangement over a diagonal slot is that it permits the yarn to revolve freely in either direction where it is desired to reverse the twist.

Of the utmost importance is the clearance space to be provided between the periphery of the coppering ring and the lower inside edge of the retaining lip 6. To give proper clearance the ring and the holder are so proportioned that the outside of the ring, while appreciably larger than the interior of the lip, is also enough smaller than the peripheral wall of the ring-receiving groove so that the ring, when forced to one side by the thrust of the engaging yarn, leaves a crescent shaped clearance space extending nearly one-third of the way around the holding lip between the holding lip and the ring so that this clearance space, at the point where the yarn is in contact with the ring, will be ample to prevent the yarn at that point from rubbing against the edge of the lip.

To make perfectly plain the practical relationship of these parts, but without prescribing exact dimensions, I may say that a coppering ring whose external diameter is very slightly under one and one-half inches may be about forty-thousandths inch larger diameter than the interior diameter of the holding down lip, while the groove in the holder may be cut in about sixty one-thousandths of an inch so as to leave a clearance space approximately twenty-thousandths inch wide at its widest or medial point. This will be several times the diameter of

the yarn to be spun, but as there is a tendency for the yarn to occupy a position some distance from this ever changing medial point of the clearance space, and if insufficient clearance is given, the yarn may be pinched between the ring and the lip which will inevitably cause the yarn to break.

By reference to Figures 1 and 2 it will be understood that the yarn pulls against the free or unsupported side of the ring subtending the clearance space both laterally and upwardly and consequence of this the side of the ring opposite the point of yarn contact has a lateral thrust outward against the outer wall of the groove, and a downward thrust against the bottom wall 7 of the groove, that is, the yarn tends to pull the free or unsupported side of the ring which it engages upward inside the lip, and correspondingly tilts the opposite side downward against the bottom of the groove.

To avoid the rubbing action against the bottom of the ring, due to its lateral movement under its continual displacement by the yarn, I prefer to make the holder in a form that will afford more of a rolling contact against the downward thrust-supporting surface of the ring since such rubbing contact may, under some conditions, roughen the bottom surface of the ring enough to unduly increase the tension.

In Figure 3 I have shown an all-metal or one-piece holder 10 provided with an interior groove for receiving the fiber coppering ring 16, the peripheral wall of said groove comprising an upper substantially vertical portion or surface 13, and a lower portion or bearing surface 12, inclined inwardly at an obtuse angle to the vertical portion 13. This oblique thrust wall, inclined at an angle of about 45° from the vertical axis, will adequately sustain the downward thrust because the lateral pressure is greater than the downward pressure, and it gives practically a rolling contact for the ring which also eliminates the rubbing action while the ring is running.

In Figures 4, 5 and 6 I have shown specifically different forms of ring and holder whose common characteristic is that the yarn-contacting surfaces of the ring do not have bearing engagement or contact with the holder, while at the same time providing the requisite degree of clearance.

In Figure 4 the fiber or "Bakelite" ring 25 is made of angular form in cross section by cutting away the outer lower corner portion of the ring sufficiently so that, when its smaller peripheral surface is engaged against the shoulder 22 of the holder, the opposite side of the larger upper portion is located the requisite distance within the inside edge of the holding down lip 24 sufficiently to give the requisite clearance, but at the same time the peripheral face of the

larger portion of the ring does not actually contact with the outer wall of the groove. The downward thrust is supported by the underneath face of the outwardly projecting larger portion of the ring, while the 70 yarn passes across from the outer periphery at the top to the bottom portion of the ring without engaging the two bearing faces which contact with the bearing surfaces of the holder. Ordinarily this form of ring would be made of non-metallic material because a metallic ring of steel or other suitable metal would be too heavy. Moreover, it will be noticed that close beneath the bottom edge of the ring lying in the holder is an inclined surface or edge 23 whose function is to guide or lift the ring when starting the frame into position where its exterior flange will ride over the rounded corner 75 of the ledge 22. A similar surface 28 is 80 found in the holder 26 for use with a metallic ring 29 whose outer flange is upwardly inclined to ride over and engage the inner portion of the inclined bearing face 27. The higher portion of the ledge 28 is close 85 enough to the lowest inmost portion of the ledge 27 to allow a very small metallic ring to shift into place when the frame is started without catching against the vertical face 90 of the shoulder 27. The pressed metal ring 29 is shown with its outer flanged portion 95 thus upwardly inclined at 29a.

In Figure 6 the holding down lip 31 projects inwardly from the holder into an externally grooved ring 33, of fiber or Bakelite, the holder being provided with a shoulder at 32 above the lip to form a bearing surface for the upper portion of the grooved ring 33 against which the yarn does not ordinarily come in contact. This form of ring must necessarily be of thin construction to keep its mass within the required weight.

In Figure 7 and 8 are shown two forms of pressed steel ring which it is believed are most satisfactory.

In this case the stiff metal base 36 carries a fiber or "Bakelite" retaining member 37, which is internally grooved to provide a lateral thrust surface that is substantially vertical, and an inwardly sloped underneath thrust surface 39, for engaging a corresponding portion of the coppering ring 35. The coppering ring is shown as having a vertical outside face, a horizontally disposed bottom face and an intermediate oblique face corresponding to the angle of inclination of the surface 39 of the holder. The size of the ring, of course, as in the other cases, is much exaggerated, and in fact the ring of the shape shown should be made of a fine grade of steel of approximately ten or eleven-thousandths of an inch in thickness, the over-all height of the ring from top to bottom being approximately three sixtieths of an inch, having reference to a 130

filling ring of the kind mentioned above. The fiber holder may be held against accidental displacement by set screws 38 passing through portions of the base 36.

5 In Figure 8 I have shown a somewhat simpler form of pressed steel ring 40 where the main portion of the ring is oblique, while its outer and top surfaces are finished off to form substantially right angled bearing surfaces.

When the coppering rail *a*, in which it will be understood that the various forms of holders used are mounted, is descending, the yarn assumes the oblique position shown in

15 Figure 1 and other figures of the drawing. On the other hand, when the coppering rail rises the yarn will assume angular position, such as indicated in dotted lines in Figure 7. It is, therefore, important that

20 the inner bottom edge of the coppering ring be finished as smoothly as other parts because on each descent of the rail the yarn comes in contact with that corner. All angles or corners exposed to contact with

25 the yarn should be slightly rounded to avoid leaving any sharp edge to scrape or cut the yarn.

When using a fiber or bakelized holder I prefer to make such holder out of tubing

30 which, when cut through on one side, has the property of contracting somewhat in both cases. To maintain the proper dimensions some means should be inserted inside such holder to resist the contracting action.

35 In the drawing I have shown the cast-metal base arranged to project inside the non-metallic holder both to prevent such contraction and also to afford a frictional grip between the holder and the base.

40 It will be observed that all forms of the ring have an annular flat-top or upper bearing surface extending to the outer edge or periphery. This is a very important feature in securing an operative ring, because

45 if this upper outside corner of the ring be rounded or bevelled the inevitable consequence thereof would be to cause the ring to partly wedge itself inside of the holding-down lip when the free side of the ring is drawn upward by the tension of the yarn.

The coppering ring is only a little larger than the inner edge of the holding-down ring and the reducing of the effective diameter of the upper bearing surface of the ring is sufficient to produce the wedging action and make it impossible to spin the yarn.

It will also be noticed that the various forms of coppering ring are cut away or reduced in diameter at their lower outside corner, which results in several advantages according to the form of this portion of the ring and of the corresponding portion of the holder. In all cases this reducing the diameter of the lower portion of the peripheral surface of the ring results in materially

shortening the distance between the point of actual contact of the yarn with the periphery of the ring and the inside thin holding lip. The rapidly revolving yarn tends to stand out or balloon away from the ring as illustrated in the drawing. If the ring be given the full diameter at its lower outside corner there is much greater likelihood that the ballooning yarn will contact with the interior edge of the holding-down lip, thereby giving it an opportunity to catch in the transverse slot which admits the yarn through the holder to the ring. By cutting away or reducing the diameter of this lower portion of the periphery of the ring the actual point of contact of the yarn against the ring periphery is raised almost to the level of the lip of the holder so that the clearance is amply sufficient to prevent any catching of the yarn in the slot which would instantly break the yarn.

The advantage of cutting away this lower portion of the ring periphery to form a bevelled bearing surface, as in the form shown in Figs. 3, 7 and 8, to provide a rolling contact for supporting the downward thrust, instead of a rubbing contact, have already been explained. Also the advantages of cutting away this portion of the ring to form an annular groove, as in the form shown in Figs. 4 and 5, to avoid all contact of the yarn with the bearing portions of the ring have been explained. Moreover, the cutting away of this lower peripheral portion of the ring is found to lessen the co-efficient of friction between the yarn and the coppering ring, which is important to the satisfactory operation of the device.

It will be seen that the filling ring for medium counts of yarn, whose dimensions and weight have been approximately indicated above for purposes of illustrating the practical application of the principles herein disclosed to a ring of this type, would have a weight not exceeding five grains per inch of the over-all diameter of the ring, a ratio which could be approximately followed for larger rings for spinning warps of medium or coarse counts. Any substantial excess weight beyond that indicated would, under ordinary conditions, prevent any spinning at all and even under very special conditions would result in such a severe tension as to cause such frequent breakages as would render the device unsatisfactory or impracticable, it being understood of course as a matter of common knowledge in the art that warp yarns, which are commonly made of longer and stronger staple than filling yarns, could stand a somewhat increased ratio on that account. The clearance ratios and the necessity for an extraordinary degree of smoothness on the yarn-engaging surfaces of the ring to secure reverse rotation are of vital importance, while the form of the ring

cross section should be such as to prevent the yarn-engaged side of the ring, when pulled upward by the yarn, from binding against the lower edge of the holding-down 5 lip.

What I claim is:

1. In a device for spinning and twisting textile fibers, the combination of an outer holding member provided with an annual 10 interior ring-receiving groove, an inner flat-top coppering ring over which the yarn has circumferential slipping engagement sufficient to eliminate any dragging of the ring by the yarn, thus permitting reverse rotation 15 of the ring, both members being proportioned to provide a crescent-like lateral clearance between them on one side sufficiently wide to prevent contact of the yarn with the upper edge of said groove when the 20 ring is pressed to the opposite side of the lateral thrust of the yarn, substantially as described.
2. In a device for spinning textile fibers, the combination of an exterior ring holder, 25 formed with an interior annular lip to resist the upward thrust of the ring, a flat-top coppering ring loosely mounted inside said holder to be rolled around the interior thereof under the lateral pressure of the revolving 30 yarn, said ring being provided with a yarn-engaging surface affording a sufficiently low frictional engagement with the yarn to cause said ring to have a true rolling engagement with the interior of the holder whereby said 35 ring is caused to rotate in a direction reverse to the revolution of the yarn, said ring and said lip being relatively proportioned to afford adequate clearance to prevent the yarn being pinched against the lower edge of the 40 lip.
3. In a device for spinning yarn, the combination of an exterior non-rotating ring holder, an interior yarn-engaging coppering ring loosely mounted in said holder to be 45 rolled around the inside thereof by the interposed revolving yarn, the ring and the holder being proportioned to leave a crescent shaped clearance space between the yarn-engaging portion of the ring and the adjacent 50 edge of the holder wide enough to prevent contact of the revolving yarn with said edge of the holder, the outer and under surfaces of the ring having a sufficiently low frictional contact with the yarn to afford the 55 requisite degree of slip of the yarn to produce a true rolling movement of the ring in the holder whereby rotation of the ring in the reverse direction to the direction of revolution of the yarn is maintained, substantially as described.
4. A coppering element for a spinning device of the class described embracing in its construction a ring having a smooth, flat upwardly exposed bearing surface for engagement with the under side of a retaining 60

lip and having the upper part of its peripheral surface of approximately cylindrical form and the lower part of said peripheral surface disposed at an oblique angle to the upper portion of said periphery to form a 70 rolling bearing surface against the holder and resisting the downward thrust of that side of the ring opposite to the contact point of the yarn.

5. A coppering element for a spinning device comprising a ring adapted to be loosely contained in an internally grooved surrounding holder, said ring having its peripheral surface formed of upper and lower circumferential portions disposed at an oblique angle to each other, the upper portion being approximately cylindrical and the lower portion being of approximately frusto-conical form, and extending to the underneath horizontally disposed bottom surface of the ring, said surfaces being polished to a smoothness that will prevent any dragging action by the yarn. 75

6. A coppering ring for a spinning device adapted to be loosely mounted in a containing holder, embracing a ring having an upwardly exposed flat bearing surface extending to the peripheral edge of the ring, and having the lower portion of its periphery cut away to reduce the vertical depth of the peripheral surface substantially below the vertical thickness of the entire ring, thereby maintaining the contact point of the yarn nearer to said top bearing surface. 80

7. A non-metallic coppering ring for a spinning device of the class described, comprising a ring of vulcanized fiber having a flat-top bearing surface, and having the lower portion of its periphery cut away to a smaller diameter. 85

8. A spinning device of the class described embracing a ring holder provided with an interior annular groove for the reception of a yarn-engaging coppering ring, said groove having its top wall horizontally disposed and having its interior peripheral wall formed by two circumferential angularly disposed annular surfaces forming bearing faces for sustaining respectively the lateral and the downward thrust of said inserted coppering ring, and a yarn-engaging coppering ring loosely mounted to be rolled around inside of said groove by the thrust of the revolving yarn against its periphery, said ring being dimensioned to leave a crescent-shaped clearance space between its periphery and the upper edge of said groove sufficient to prevent contact of the yarn with said edge. 90

9. A device for spinning yarn embracing an exterior internally grooved ring holder, an interior yarn-engaging and guiding coppering-ring loosely mounted in said holder to be rolled around in said groove by the interposed revolving yarn, the ring and the 125 130

- holder being proportioned to leave a crescent-shaped clearance space between the peripheral yarn-engaged face of the ring and the adjacent edge of the grooved holder
5 wide enough to prevent contact of the revolving yarn with said edge of the holder, the outer and the under surface of the ring having a sufficiently low frictional contact with the yarn to afford the requisite degree
10 of slip of the yarn to produce a true rolling movement of the ring in the holder, whereby rotation of the ring in the reverse direction to that of the revolving yarn is maintained, said ring being of a weight not substantially in excess of five grains per inch of its over-all diameter.
15

In witness whereof, I have subscribed the above specification.
